UNITED STATES PATENT OFFICE.

JOHN FREDERICK BILLENSTEIN, OF CLEVELAND, OHIO.

FLYING-MACHINE.

1,279,231.

Specification of Letters Patent. Patented Sept. 17, 1918.

Application filed April 12, 1916. Serial No. 90,647.

To all whom it may concern:

Be it known that I, JOHN FREDERICK BILLENSTEIN, a citizen of the United States, residing at Cleveland, in the county of 5 Cuyahoga and State of Ohio, have invented certain new and useful Improvements in Flying-Machines; and I do hereby declare the following to be a full, clear, and exact description of the invention, such as will 10 enable others skilled in the art to which it appertains to make and use the same.

The invention relates to improvements in flying machines.

The object of the present invention is to 15 improve the construction of flying machines and to provide a simple, practical, and safe flying machine of comparatively inexpensive construction adapted to be operated either manually or by a motor and equipped 20 with means for instantly bringing into action a parachute which will be adapted to enable the machine in event of accident to float gently to the ground without injury to either the machine or the occupant thereof.

25 A further object of the invention is to provide a flying machine of this character adapted to be easily guided and controlled and provided with means for enabling it to hover or flutter or ascend without moving 30 forwardly so that missiles may be accurately directed against an object.

With these and other objects in view the invention consists in the construction and novel combination and arrangement of 35 parts hereinafter fully described, illustrated in the accompanying drawings and pointed out in the claims hereto appended, it being understood that various changes in the form, proportion and minor details of construction may be resorted to without departing from the spirit or sacrificing any of 40 the advantages of the invention.

In the drawings—

45 Figure 1 is a side elevation of a flying machine constructed in accordance with this invention,

Fig. 2 is an end elevation of the same,

Fig. 3 is a plan view, the top being partly broken away to illustrate the construction of 50 the mechanism of the flying machine,

Fig. 4 is an enlarged detail sectional view illustrating the construction of the combined top and parachute.

55 Fig. 5 is a transverse sectional view illustrating the construction of the vibratory concavo-convex blade,

Fig. 6 is a detail sectional view illustrating the construction of the valves of the same,

Figs. 7 and 8 are detail views of the 60 clutches for connecting the propellers to the driving shaft,

Fig. 9 is a detail sectional view of the tail blade or plane.

Like numerals of reference designate corresponding parts in the several figures of 65 the drawings.

In the accompanying drawings in which is illustrated the preferred embodiment of the invention, the flying machine which is 70 of the aeroplane type comprises in its construction, a supporting frame 1 mounted upon suitable wheels 2 and 3, the wheels 2 being located at opposite sides of the frame and being of greater diameter than the 75 wheels 3 which are located at the front and back of the frame and which are preferably of the caster wheel type for guiding the machine when the same is running on the surface of the ground. The wheels in practice 80 will be provided with cushioned tires preferably filled with powdered cork or other suitable means for rendering the wheels buoyant to enable the machine to float on the surface of the water. The cushioned 85 tires may be made of any desired size to secure this result and the frame which is rectangular in plan view may be constructed in any suitable manner and braced by any suitable means to secure the requisite 90 strength and lightness.

The frame of the flying machine is provided with a fabric top 4 constructed of suitable material and having accordion plaited side portions and end portions 5 adapted to 95 be normally maintained in a closed or compact condition and secured in such folded position by means of clips 6 connected with a cord 7 having an operating portion 8 adapted to disengage the clips from the accordion plaited or folded marginal portions 5 to enable the top to expand and form a parachute. The folded or accordion plaited marginal portions are illustrated or shown exaggerated in the accompanying drawings 100 but in practice a sufficient number of folds or plaits may be compactly arranged so as not to interfere with the use of the fabric top of the machine as a plane if so desired, and instead of securing the plaited or folded 110 marginal portions by means of the clips any suitable fastening devices may of course be

provided. Also the parachute top may be mounted in any other desired manner as will be readily understood. It will be seen that when the parachute top is released that it 5 will form a parachute and permit the machine in event of accident to float gently to the ground and that injury both to the machine and the occupant thereof will be thereby avoided. This will enable many accidents 10 to be avoided as the parachute is always in position for instant use.

The machine is equipped at opposite sides with hinged stabilizing planes 9 pivotally mounted at 10 and equipped with suitable 15 handles or operating levers 11 carrying latches 12 for engaging toothed segments 13 or other suitable locking means for securing the side planes 9 in their adjustment. The handles 11 are designed to be located within 20 easy reach of the seat 14 mounted on the frame for the convenience of the aviator. Also the machine is provided with a tail plane 15 having a depending blade 16 and also equipped with a series of pivoted slats 25 17 connected with a suitable operating device 18 which may consist of a rod, cord or other suitable means adapted to open the slats to permit the passage of air therethrough to prevent gusts of wind from affecting the 30 equilibrium and stability of the flying machine by operating on the tail blade which may be of any desired size and shape. Also in practice the machine will be provided with a suitable rudder and it is equipped at the 35 front with a movably mounted front elevating plane 19 having a depending blade 20 and hinged at the front to permit it to be arranged at different angles or inclinations. The front adjustable plane 19 is provided with 40 a pair of handles 21 adapted to be gripped by the operator and a suitable locking device 22 is provided for securing the front plane in its adjustment. The flying machine which may be operated either manually or by means 45 of a motor (not shown) is equipped with front and rear propellers 23 and 24, mounted on front and rear propeller shafts 25 and 26 and adapted to be engaged by suitable clutches 27 which cause rotation of the propellers in one direction for forward propulsion when the propeller shafts are driven 50 forwardly but which permit the propellers to remain stationary when the propeller shafts are driven in a retrograde direction 55 as hereinafter fully explained, for the purpose of permitting independent operation of the vibratory concavo-convex blades 28. The propellers which are loose on the propeller shafts and are held from sliding off of the 60 shafts by the clutch 27 are provided with projections 29 which are adapted to be engaged by shoulders 30 of sliding sleeves 31. The shoulders engage the projections of 65 the propellers when the sliding sleeves are moved forwardly and the sliding sleeves are

provided with inclined or angularly disposed faces 32 which permit the sleeves to ratchet past the projections when the shafts are rotated rearwardly.

The sliding sleeve is urged into engagement with the coacting projections by means of a coiled spring 33 and it is locked against relative rotary movement by a pin or key 34 piercing the propeller shafts and operating in a slot 35 of the sleeve 31. The propellers 75 simultaneously actuate the flying machine and the propeller shafts which extend inwardly from the propellers in a direction longitudinally of the flying machine are equipped at their inner ends with pinions 80 38 which mesh with a gear wheel 39 mounted on a driving shaft 40 journaled in suitable bearings and equipped with pedals 41 to enable the aeroplane to be operated in a manner similar to an ordinary bicycle but 85 any suitable motor may be employed for actuating the propellers. The propeller shafts are equipped with eccentrics 42 operating in eccentric straps 43 which are provided with pivots 44 extending through an 90 ear 46 of the eccentric strap and through slots 47 of levers 48. The levers 48 which are fulcrumed intermediate of their ends at 49 are disposed transversely of the machine at the front and rear portions thereof 95 and their outer arms carry the concavo-convex blades 28, so that when the propeller shafts are rotated the said blades 28 will be vibrated and moved upwardly and downwardly. The blades 28 which present lower 100 concaved faces are provided at intervals with openings 49^a which during the downward movement of the blades 28 are closed or covered by valves 50. The valves 50 are preferably flap valves and open under the 105 pressure of the atmosphere on the upward movement of the blades 28 and the said blades 28 in their downward movement are adapted to exert a lifting force which may be sufficient to sustain the flying machine in 110 an elevated position to enable the flying machine to hover or flutter and they may also be operated with sufficient power to exert a lifting force for elevating the flying machine. The blades 28 are equipped with 115 sleeves 52 mounted on the oscillatory levers 48 and provided with handles 53 in order to allow of rotation and adjustment of the blades 28 upon the shafts 48 so as to enable the concavo-convex blades to be tilted forwardly or inclined from the horizontal and to be adjusted for exerting a lifting action 120 and a propelling action to increase the speed of the flying machine. Any suitable means may be employed for locking the blades in 125 their adjustment—a pawl and ratchet mechanism for instance not shown in the drawings—and various means may be provided for oscillating the levers which carry the blades in their upward and downward move- 130

ment. When the propeller shafts are rotated forwardly the propellers are operated simultaneously with the blades 28 but when it is desired to actuate the blades 28 without operating the propellers the driving shaft is rotated rearwardly which oscillates the levers 48 and at the same time enables the slideable sleeves to ratchet over the projections of the propellers whereby the latter 10 are prevented from rotating and moving the machine forwardly.

In order to further increase the stability of the flying machine, the latter is equipped with a central depending weight 54 connected with the bottom of the frame by ropes 55 or other suitable flexible connections and also provided with a hoisting rope or connection 56 to enable the weight to be raised and lowered to vary the effect of the 20 same and also to lift it out of the way when the machine is to descend to the surface of the ground.

What is claimed is:—

1. A flying machine of the class described 25 including a shaft, an eccentric mounted on the shaft, an eccentric strap arranged on the eccentric, levers extending in opposite directions from the eccentric strap and connected with the same, said levers being connected 30 at their inner ends, and vibratory blades connected with the levers at the outer ends thereof and movable upwardly and downwardly and provided with valved apertures adapted to open automatically on the upward movement and close on the downward movement.

2. A flying machine of the class described 35 including an eccentric, an eccentric strap ar-

ranged on the eccentric, oscillatory levers extending in opposite directions from the eccentric strap and connected at their inner ends to the same, said levers being fulcrumed intermediate of their ends, and vibratory blades having sleeves arranged on the outer ends of the oscillatory levers for rotary movement and angular adjustment and provided with operating and adjusting handles.

3. A flying machine of the class described 40 including a propeller shaft adapted to rotate in both directions, propelling means mounted on the propeller shaft, an eccentric also mounted on said shaft, vibratory blades actuated by said eccentric and a clutch mounted on the propeller shaft and arranged to rotate the propelling means when the shaft is rotated in one direction only whereby the blades may be continuously operated regardless of the operation of the 45 propelling means.

4. A flying machine including a propeller shaft adapted to rotate in both directions, means for actuating the same, propelling means on said shaft and clutching means operably connecting the propelling means to the shaft when the latter is rotated in one direction only, and a vibratory blade actuated by the propeller shaft while the same is rotated in either direction.

In testimony whereof I affix my signature 50 in presence of two witnesses.

JOHN FREDERICK BILLENSTEIN.
